US00D976301S

(12) United States Design Patent (10) Patent No.: US D976,301 S
(45) Date of Patent: * Jan. 24, 2023

(54) BABY MONITOR

(71) Applicant: DOKOKI AG, Hindelbank (CH)

(72) Inventor: Marc Zinner, Mühlethal (CH)

() Term: 15 Years

(21) Appl. No.: 35/510,308

(22) Filed: Aug. 27, 2020

(80) Hague Agreement Data

Int. Filing Date: Aug. 27, 2020

Int. Reg. No.: DM/210103

Int. Reg. Date: Aug. 27, 2020

Int. Reg. Pub. Date: Sep. 18, 2020

(30) Foreign Application Priority Data

Feb. 28, 2020 (DE) 40 2020 100 211.9

(51) LOC (14) Cl. 16-01

(52) U.S. Cl.

USPC D16/203

(58) Field of Classification Search

USPC D16/200, 202-205, 208, 218, 219, 242

CPC G03B 17/02; G03B 17/04; G03B 17/56;
G03B 19/04; G03B 15/03
